UNITED STATES PATENT OFFICE.

PAUL BROWN KLUGH, OF CHICAGO, ILLINOIS, ASSIGNOR TO THE CABLE COMPANY, OF CHICAGO, ILLINOIS, A CORPORATION OF ILLINOIS.

MECHANICAL MUSICAL INSTRUMENT.

1,183,738.

Specification of Letters Patent.

Patented May 16, 1916.

Application filed November 19, 1910. Serial No. 593,203.

To all whom it may concern:

Be it known that I, PAUL BROWN KLUGH, a citizen of the United States, residing at Chicago, in the county of Cook and State 5 of Illinois, have invented a certain new and useful Improvement in Mechanical Musical Instruments, of which the following is a full, clear, concise, and exact description, reference being had to the accompanying 10 drawings, forming a part of this specification.

My invention relates to mechanical musical instruments and especially to a type of instrument commonly called a player piano. 15 or piano player.

The present invention relates more particularly, although not exclusively, to the accentuation of certain notes or series of notes to bring out solo effects.

20 The object of the invention, when applied to piano players and player pianos, is to provide means for producing the aforesaid solo effects in an improved manner.

Certain broad features of the solo device 25 herein set forth are claimed in my co-pending application, Serial No. 554,140, filed April 8, 1910.

In the form of carrying out the invention herein shown, I employ blow striking 30 members, operated by power pneumatics, and removable means to limit the stroke of said blow striking members. Broadly speaking, I also provide resilient means to change the strength of the blow.

35 I will describe my invention more in detail by reference to the accompanying drawings, illustrating several forms of carrying out the invention, in which:

Figure 1 is a side elevation, partly in section, setting forth the piano action, the operating pneumatics, the keys, and the music roll; Fig. 2 sets forth my improved music sheet as described in my aforesaid co-pending application; Fig. 3 is a front elevation 40 of a part of the mechanism shown in Fig. 1; and Figs. 4 and 5 show modifications of the structure set forth in Fig. 1.

Referring more particularly to Fig. 1, I show a mechanical musical instrument having strings 1 to be struck by the piano action. The latter involves the usual hammers 2 and actuating mechanisms therefor. The piano action is operated by pneumatics 5 governed by valve mechanisms 6. The 50 valve mechanisms are connected by means

of tubes 7 to the tracker board 8 where a music sheet 9 in its well understood operations selectively controls the actuation of the pneumatics 5. Piano keys 10 may also operate the action as is well understood. 60

In accordance with my aforesaid co-pending application, I provide supplemental pneumatics 11, served by tubes 12 and leading to apertures 13 in the tracker board, for accentuating certain notes in order to 65 produce what are called solo effects. The ordinary apertures 14 in the tracker board 8 are associated with the tubes 7. In accordance with my aforesaid co-pending application, the music sheet has narrow openings or perforations 15 which, in the progress of the sheet over the tracker board, co-operate only with the apertures 14, and wide openings or perforations 16 which co-operate with both apertures 14 and 13 of 70 a given set.

It will of course be understood that each set of adjacent apertures 13 and 14 serve the actions for the same note. My supplemental pneumatics 11, through the medium 80 of adjustable bars or rods 17, control stops 18, which can be inserted or withdrawn from between the arms or levers 3 and an abutment 19. When a stop 18 is in place, as shown in Fig. 1, the movement of the corresponding arm or lever is limited in that the downward pull of the respective pneumatic 5 can draw it only tightly against the stop 18, whereas, if the supplemental pneumatic 11 controlling this stop is actuated to withdraw it toward the left, referring to 85 Fig. 1, the arm 3 may move the entire length of its stroke when the pneumatic 5 is actuated. It will be seen therefore that a supplemental solo pneumatic 11 serves when 90 actuated to permit a louder tone of the particular note under consideration, because of the greater extent of movement of the respective power pneumatic in operating. 95

In Fig. 4, I set forth special wedge shaped stops 20 which in turn limit the strokes of the arms 3 and at the same time limit the strokes of the power pneumatics 5. 100

In Fig. 5, I set forth a very important structure in that I employ resilient means, in this instance consisting of springs 21 under the control of the supplemental pneumatics. It will be seen that, in the structure of Fig. 5, I interpose removable stops 105 which may again be used to limit the strokes 110

of the arms 3 or the power pneumatics 5, but which removable stops are resilient and afford yielding resistive effects when associated with the operating mechanism of an instrument of the class specified.

5 The tracker board and music sheet disclosed herein are set forth and claimed in a copending application of mine, Serial No. 554,142, filed April 8, 1910, tracker board and music sheet.

10 While I have herein shown and particularly described the preferred embodiment of my invention, I do not mean to limit myself to the precise construction and arrangement as herein set forth, but

15 Having thus described one embodiment of my invention, what I claim as new and desire to secure by Letters Patent is:

20 1. A device of the character described comprising blow-striking members, power pneumatics to operate same, an abutment, removable stops to limit the strokes of said power pneumatics capable of occupying positions intermediate said abutment and said members, and means for operating said stops to remove them from between said abutment and said members.

25 2. In a device of the class described in combination, a power pneumatic, an action comprising a lever operated by said pneumatic, an abutment, a device normally interposed between said abutment and said lever, and mechanism for withdrawing said device from between said abutment and said lever.

30 3. A device of the character described comprising blow striking members, power pneumatics to operate same, an abutment, means movable between said members and said abutment to limit the strokes of said members, and solo pneumatics to operate said means.

35 4. A device of the character described comprising blow striking members, power pneumatics to operate same, an abutment, resilient means movable between said members and said abutment to limit the strokes of said members, and solo pneumatics to operate said resilient means.

40 5. A device of the character described comprising blow striking members, power pneumatics to operate same, an abutment, a spring movable between said members and said abutment to limit the strokes of said members, and solo pneumatics to operate said spring.

45 6. A device of the character described comprising blow striking members, power pneumatics to operate same, removable stops to limit the strokes of said power pneumatics, and solo pneumatics to operate said removable stops.

50 7. In a device of the class described in combination, a power pneumatic, an action comprising a blow striking member operated by said pneumatic, a fixed abutment, a

device normally interposed between said abutment and said member, and mechanism whereby said device may be withdrawn from between said member and said abutment.

75 8. In a device of the class described in combination, blow striking members, power pneumatics for operating said members, an abutment, means movable between one of said members and said abutment, and devices to operate said means.

9. In a device of the class described in combination, a power pneumatic, an action comprising a lever operated by said pneumatic, an abutment, a device movable between said lever and said abutment, and a solo pneumatic for moving said device.

10. In a device of the class described in combination, a power pneumatic, a player action comprising a lever operated by said pneumatic, an abutment, a device normally interposed between said abutment and said lever, and a solo pneumatic for withdrawing said device from its normal position.

100 11. In a device of the class described in combination, a power pneumatic, a player action comprising a lever operated by said pneumatic, an abutment placed in proximity to one end of said lever, a movable device normally interposed between said abutment and said lever, and a solo pneumatic for withdrawing said device from between said abutment and said lever.

105 12. In a device of the class described in combination, a power pneumatic, a player action comprising a lever operated by said pneumatic, an abutment placed in proximity to one end of said lever, a movable device normally interposed between said lever and said abutment to prevent the complete expansion of said pneumatic, and a solo pneumatic for withdrawing said device from its position between said lever and said abutment.

110 13. In a device of the class described, a power pneumatic, a player action operated by said pneumatic and comprising a lever, an abutment, a spring movable between said lever and said abutment and normally in position to resist the closing of said power pneumatic, and a solo pneumatic for removing said spring from its normal position.

115 14. In a pneumatic instrument in combination, a power pneumatic, an action unit operated by said pneumatic comprising a plurality of members one of which is a note sounding member, an abutment, a device normally interposed between said abutment and one of said members, and mechanism whereby said device may be withdrawn from between said one of said members and said abutment.

120 15. The combination with a piano action, of a pneumatic for actuating the same, and means for opposing the operative movement

of the pneumatic so as to vary the effect of its operation upon the piano action.

16. The combination with a piano action, of a pneumatic for actuating the same, and means for resisting the operative movement of the pneumatic so as to vary the effect of its operation upon the piano action.

17. The combination with tone sounding mechanism and means for actuating the same, of pneumatic means for operating said actuating means, intermediate mechanism between the two said means, and means for automatically controlling said intermediate mechanism to vary the operation of said actuating means.

18. The combination with blow striking members, of pneumatics for actuating said members, and supplemental pneumatics combined with mechanism for acting upon said first mentioned pneumatics so as to intercept the blow striking movement thereof.

19. The combination with blow striking members, of pneumatics for actuating the same, and supplemental pneumatics combined with mechanism for controlling the actuation of said members by said pneumatics, by the movement of abutments into and out of the paths of the blow striking movements of said members.

20. The combination with a tracker having front and rear sets of ports, a set of pneumatics connected with the front set of ports, blow striking members actuated by said pneumatics, a second set of pneumatics connected with the rear set of ports, and abutments controlled by said second set of pneumatics and adapted to be interposed into and withdrawn from the paths of the blow striking movements of said members.

21. The combination with a piano action, of a pneumatic action including a set of pneumatics and mechanism associated therewith for actuating said piano action and also including other pneumatics combined with mechanism for varying the action of said first set of pneumatics upon the piano action by limiting the extent of movement of the mechanism controlled by said first set of pneumatics.

22. The combination of a tracker having front and rear rows of ports, a piano action, and a pneumatic action including a set of pneumatics combined with mechanism for actuating said piano action and also including other pneumatics combined with mechanism for limiting the actuating movements of said first set of pneumatics upon said mechanism combined therewith for actuating said piano action, said pneumatics being connected with said rows of tracker ports, said set of pneumatics with one row and said other pneumatics with the other row.

23. The combination with a piano action, of a set of pneumatics combined with levers arranged to be operated by said pneumatics

to actuate said piano action, and a second set of pneumatics combined with abutments arranged to be moved into and out of position to control the movements of said levers.

24. The combination with a piano action, of a set of pneumatics combined with levers arranged to be operated by said pneumatics to actuate said piano action, and a second set of pneumatics combined with abutments arranged to be moved into and out of position to shorten the blow striking movements of said levers.

25. The combination with tone sounding mechanism, of pneumatic means for operating the same, lever devices interposed between said pneumatic means and said tone sounding mechanism, and automatically operated pneumatic means for controlling the actuation of said lever devices to vary the operation of said tone sounding mechanism.

26. The combination with a piano action, of a set of pneumatics combined with levers arranged to be operated by said pneumatics to actuate said piano action, and a second set of pneumatics combined with resilient abutments adapted to control the length of movement of said levers.

27. The combination with a tracker having two rows of apertures, of blow striking members, a set of pneumatics connected with the apertures of one of said rows, said pneumatics being arranged to actuate said blow striking members, a second set of pneumatics connected with the apertures of the other row of apertures in the tracker, and means controlled by said second set of pneumatics for opposing the blow striking action of said members.

28. The combination with a piano action, of a tracker having two rows of apertures, a set of pneumatics connected with the apertures of one of said rows, said pneumatics being arranged to actuate the units of the piano action, a second set of pneumatics connected with the apertures of the other row of tracker apertures, and means controlled by said second set of pneumatics for obstructing the operation of the piano action.

29. The combination of a power pneumatic, a spring opposing the action of said pneumatic, and a second pneumatic arranged to act upon said spring and remove the opposition of the same from the action of the first mentioned pneumatic without actuating the latter.

30. The combination with blow striking members, of pneumatics for actuating the same, resilient abutments opposing the blow striking movements of said members, and means for withdrawing said abutments without actuating said pneumatics.

31. The combination with a tracker, a sheet provided with note characters and cooperating with said tracker, and operative means controlled as to operation through

said tracker by a note character of said sheet, of independently movable means controlled by the same said note character of said sheet to resist the operation of said operative means.

32. The combination with a tracker, a sheet provided with note characters and co-operating with said tracker, note sounding devices, and means controlled as to operation through said tracker by a note character of said sheet to operate said devices, of independently movable means controlled by the same said note character of said sheet to resist the operation of said device operating means.

33. The combination with a tracker and a sheet provided with note characters and co-operating with said tracker, of operative means and independently movable means to resist the operation thereof, both of said means being controlled in operation through said tracker by the note characters of said sheet.

34. The combination with a tracker, a sheet provided with note characters and co-operating with said tracker, and note sounding devices, of means to operate said devices and independently movable means to oppose the operation thereof, both of said means being controlled in operation through said tracker by the note characters of said sheet.

35. The combination with a tracker, a sheet provided with note characters and co-operating with said tracker, and power actuated note sounding devices, of independently movable means operating to resist the actuation of said devices, said devices and said means being controlled in operation through said tracker by the note characters of said sheet.

36. The combination with a tracker and a perforated sheet co-operating therewith, of operative means and independently movable

means to resist the operation thereof, both of said means being controlled in operation through said tracker by the same perforation of said sheet.

37. The combination with a tracker, a perforated sheet co-operating therewith, and note sounding devices, of means to operate said devices and independently movable means to oppose the operation thereof, both of said means being controlled in operation through said tracker by the same perforation of said sheet.

38. The combination with a tracker, a perforated sheet co-operating therewith, and power actuated note sounding devices, of independently movable means operating to resist the actuation of said devices, said devices and said means being controlled in operation through said tracker by the same perforation of said sheet.

39. The combination of a tracker having two sets of apertures, a piano action, means operated through the apertures of one of said sets for operating said piano action, and means operated through the medium of the other set of apertures for controlling the extent of movement of members of said piano action between the hammers and keys.

40. The combination with a tracker having two sets of apertures, of a piano action, means operable by means of the apertures of one of said sets for actuating the piano action, and means operable by means of the apertures of the other set for limiting the blow striking movements of members of said action between the hammers and keys.

In witness whereof, I hereunto subscribe my name this 2nd day of November A. D., 1910.

PAUL BROWN KLUGH.
